Application April 22, 1938, Serial No. 203,487
 In Germany April 26, 1937

7 Claims. (Cl. 250—27)

The present invention relates to cathode ray tube arrangements, more particularly for television purposes wherein means comprising at least one pair of deflecting plates are provided for deflecting the cathode ray in two directions perpendicular to one another.

It is known that a large bundle of rays which, when not deflected, is focussed sharply on the screen will not give a sharp image point in the case of deflection beyond a critical angle. It is also known that this critical angle can be increased if the two plates are supplied with reverse phase deflecting voltages so that their potentials oscillate symmetrically with respect to the anode potential. New investigations, however, have shown that even in this case an enlargement of the image point takes place if the beam is deflected beyond an angle of about 17°. For several reasons, however, it is desirable to have considerably greater deflections of the ray with full sharpness of the edges of the picture. Then can be obtained either larger pictures with a given length of tube or shorter tubes with a given size of picture. In the latter case it is also possible, for electron optical reasons, to obtain a smaller image point and a greater density of light.

It is an object of the present invention to perform a wide angle deflection in cathode ray tubes, more particularly for television purposes, and at the same time to maintain an irreproachable sharpness of the picture over its entire area.

According to the invention, in a cathode ray tube arrangement of the above mentioned type, wherein the cathode ray tube comprises an anode which is mounted immediately adjacent to the deflecting plates at their side facing the cathode and is connected to a source of constant potential, and there are provided means for producing the effect of a common bias applied to the deflecting plates, which is positive with respect to the anode and varies in rhythm with the deflecting voltage built up across the deflecting plates, the peak value of the common bias being preferably substantially equal to one half of the peak value of the deflecting voltage.

The invention will be better understood with the aid of, and further features of the invention will be apparent from the following more detailed description and the accompanying drawings in which—

Fig. 1 illustrates an experimental circuit used for obtaining the effects shown by Figs. 2a and 2b,

Figs. 3, 4, 5, 7, and 8, in a purely diagrammatic fashion and by way of example, illustrate cir-

cuits for avoiding the effect according to Fig. 2a, whilst

Fig. 6 is a graph showing the deflecting voltage and an example of a common bias applied to the deflecting plates.

The following experiment illustrated by Fig. 1 has been made for investigating the errors of an electro-static deflecting system:

In a cathode ray tube there are provided two deflecting plates 1 and 2 beyond an anode 3. The bundle of cathode rays 4, in the non-deflected condition, is focussed sharply on to the screen 5. The battery 6 supplies to the plates the deflecting potential. In the example shown the ray is thus deflected downwards. In parallel with the battery 6 there is connected a potentiometer 7, the wiping contact of which is connected with the anode 3. If a certain deflection is adjusted, it can be ascertained that beyond the critical angle of deflection the sharpness of the point is maintained in full if plate 1, which is connected to the negative terminal of the battery, is at the same time connected to the anode and the positive plate exhibits in relation to the ray the full deflecting potential. In Fig. 1 this connection is obtained by displacing the wiper of the potentiometer towards the right. If the opposite adjustment is made, i. e., the positive plate connected to the anode and the negative plate allowed to oscillate in relation to the ray, the sharpness of the edge of the picture will be considerably poorer.

Further detailed investigations have shown that not a marginal field nor a variation of the speed of the ray, but probably a space charge effect is causing the described effect.

In Fig. 2a there is shown the "wrong" connection, the anode 3 being connected with the positive plate 2, and in Fig. 2b the "proper" connection. In Fig. 2a the point of intersection of the single rays is displaced from the plane of the screen 5 towards the anode to the point 5a. The focal distance of the system is shortened and the image loses its sharpness at the edge.

In the proper connection, Fig. 2b, the anode being connected with the negative plate, the reverse effect occurs. The rays nearer the positive plate are deflected somewhat more strongly than those opposite to the negative plate. The focal distance of the system is extended from 5a to 5b. The image point remains on the screen.

It has been found that any variation of the sharpness of the image point during the whole deflection period can be avoided when both plates 55 are furnished, in addition to the deflecting po-

tentials, with a common varying bias increasing with the absolute value of the deflecting voltage in such a way that the potential of the deflecting plates is always higher than or at least equal to the potential of the anode. It will be understood from the following that the desired effect, i. e., the effect of a common bias applied to the deflecting plates, can also be obtained by circuit means which do not supply the deflecting plates with a "common bias" in the strict sense of the word.

The simplest way to realize the desired effect is to provide means connecting that deflecting plate which is instantaneously negative with the anode. That means that the connection between plates and anode must be commutated twice in a complete deflection period from the left to the right and back when push-pull deflection is used. As regards the technical reduction to practice the following circuit illustrated by Fig. 3 would be conceivable in principle:

The two plates 1 and 2 are connected with the secondary of a deflection transformer 8 the primary of which is fed by a relaxation oscillator 23. The mean point of the secondary is connected by way of a leak resistance 9 with the anode 3. Two rectifiers 10a, 10b (diodes are shown in the drawings) are connected by the cathode with the plates and by the anodes with the tube anode 3. Neither of the plates is then able to become negative in relation to the tube anode, whereas the potential of the instantaneously positive plate is able to oscillate with respect to the anode without obstruction.

Consequently each plate carries alternately constant anode potential for one half period of deflection and a positive saw-tooth potential for the next half period, the potentials of both plates having a phase difference of one half period. Thus the voltage between both plates has a saw-tooth wave form the amplitude of which can easily be made equal to the required deflecting voltage. The effect is exactly the same as if the plates were oscillating in push-pull and both plates had a common positive bias increasing with the absolute value of the deflection. This results from the fact that the mean potential of the deflecting condenser varies proportional to and with the same frequency as the absolute value of the potential difference produced by the reverse phase voltages which would appear at the terminals of the secondary winding of transformer 8, if ordinary push-pull operation were used.

The problem can also be solved in a similar way by means of grid controlled thermionic tubes according to Fig. 4. Two amplifying tubes 19 and 19' are via condensers 20 and 20' coupled with the two deflecting plates 1 and 2. 32 is the common anode battery of the tubes, 33 and 33' are the anode resistances. The grids of the tubes are provided with grid current limiting resistances 21 and 21' and have no bias voltage. Thus the tubes work as class B-amplifiers and produce exactly the desired deflection voltages. Instead of utilizing the grid currents for cutting off the undesired exciting half-wave a special pair of rectifiers, for example two crystal detectors, can naturally also be included on the secondary side of 8, i. e., in front of the grids of the tubes, in which case the tubes, as normal class A-amplifiers, would then have a purely amplifying function to perform.

A disadvantage of this circuit is that associated with all class B-amplifiers consisting in

the fact that in the vicinity of the zero point of deflection there is a departure from the linearity, which can only be avoided with difficulty by careful biasing and the selection of equal tubes.

- 5 5 This comparatively harmless zero anomaly in the case of sound amplifiers can be intolerable in television.
- 10 The circuit system shown diagrammatically in Fig. 5 and more detailed in Fig. 7 is free of this disadvantage. The deflecting plates are again connected with the secondary 8 of a relaxation transformer the mean point of which, however, is not, as usual connected with the anode 3 directly, a variable bias v being included between.
- 15 15 The additional voltage v must be approximately one-half of the deflecting voltage and traverse a positive maximum twice during one relaxation period.

20 In Fig. 6 there have been entered the courses of the deflecting voltage d and the additional voltage v . As measurements have shown, the course of v requires to be represented, at least in the case of a spherical or plane screen, not by a straight, but by a parabolic curve in order to obtain the best compensation. This fact enables the potential v to be produced without the use of rectifying tubes simply by integration of a linear relaxation curve, e. g., by charging a second condenser via a rather high resistance by the voltage of a usual relaxation condenser.

25 In Fig. 7 there is shown an embodiment of the scheme according to Fig. 5. 16 is the relaxation condenser charged via resistance 17 and discharged by the grid controlled thermionic tube 18. The condenser is coupled to an amplifying tube 15 the anode circuit of which contains in series the primary coils of the transformers 8 and 12. The transformer 8 for the deflecting voltage d is shunted on the primary side by a 30 relatively low resistance 11 in order to enable it to yield on its secondary terminals a linear relaxation voltage. The secondary of 8 should have a self-induction which is so small that the natural period of the secondary circuit comprising 35 the deflecting plates and the leads to them is equal to or preferably smaller than the return period of the ray. The transformer 12 for the voltage v is tuned considerably lower than the transformer 8. It has preferably on the primary and secondary side two to three times more windings than 8 and is, like 8, shunted on its primary side by a resistance 13. The exact adjustment of the voltage v takes place by varying experimentally the capacity of the integrating condenser 14 or the charging resistance 34. In the case of a 400-line image it amounts to approximately $300\mu\mu f$. The voltage arising at the secondary terminals of 12 is already the desired parabolic voltage v . (The same effect can naturally also be obtained by employing on the primary side a larger condenser.) The secondary terminals of 12 are connected to the anode 3 respectively via a damping resistance 24 of approximately 10^4 to 10^5 ohms to the mean point of the secondary of 8 in order to prevent an oscillation of the circuit 1—8—2 initiated by the return beat and otherwise disturbing the linearity of the deflection.

40 40 To enable the transformers 8 and 12 to function independently of each other the tube 15 must be a pentode, as otherwise the anode current would be affected by the variable impedances of the transformers and would not be an undistorted reproduction of the purely linear relaxa-

tion potential resulting at the storage condenser 16.

The arrangement described above can be employed also in the case of electrostatic deflection in both coordinates. Mixed deflection, however, has also been found particularly suitable, the slow deflection being performed magnetically, and the above-described method of positive deflection according to the invention being applied only to the rapid movement caused by deflecting plates. As compared with the method of performing rapid deflections magnetically, the method according to the invention has the advantage of requiring a considerably smaller power input. It has been carried out up to angles of approximately $2 \times 25^\circ$ without any limit having been reached.

The effect of the positive bias of the plates is only sufficient alone if the spacing of the plates does not exceed the thickness of the cross-section of the ray when entering the plates. Even greater angles of deflection can, however, be obtained if, together with the plates, the electronic lens is also controlled by the rectifying potential or by a part of the same in such fashion that the refractive power of the reproducing lens decreases when the angle of deflection increases. This can be performed in the case of both magnetic as well as electric lenses.

A circuit system for combined plate and lens control is shown in Fig. 8. The linear relaxation potential 23 is amplified by a screening grid tube, preferably a pentode 15. The anode current flows in series through the deflecting transformer 8, which is shunted by the resistance 11. The anode current then traverses a part of the potentiometer 35 the whole resistance of which remains in parallel to the primary of the transformer 12 so that its excitation is able to be adjusted by the slider of 35. By means of the condenser 14 the secondary voltage of 12 is integrated, as described above. At the potentiometer 28 a suitable part-potential, which can be adjusted by observing the effect at the image field, is tapped and is passed via condenser 27 to the lens electrode 26. The lens in this case is shown as an electro-static one. It is furnished via the high resistance 29 with a bias by a tapping on the potentiometer 30 shunting the anode battery 31. This bias is so chosen that the centre of the picture is sharp.

I claim:

1. In a cathode ray tube arrangement comprising means including a cathode for producing a cathode ray, a screen, means including an anode for focusing said cathode ray on said screen, and means including a pair of deflecting plates for deflecting said cathode ray, said anode being mounted immediately adjacent to said deflecting means at their side facing said cathode and being connected to a source of constant anode potential; means for producing the effect of a common, variable positive bias applied to said deflecting plates with respect to said anode and increasing with the absolute value of the deflection of said cathode ray.

2. In a cathode ray tube arrangement comprising means including a cathode for producing a cathode ray, a screen, means including an anode for focusing said cathode ray on said screen, and means including a pair of deflecting plates for deflecting said cathode ray, said anode being mounted immediately adjacent to said deflecting means at their side facing said cathode and being connected to a source of constant anode potential; means for producing the effect of a com-

mon, variable positive bias applied to said deflecting plates with respect to said anode and increasing with the absolute value of the deflection of said cathode ray, said last mentioned means comprising a circuit connecting the instantaneously negative of said plates to said anode.

3. In a cathode ray tube arrangement comprising means including a cathode for producing a cathode ray, a screen, means including an anode for focusing said cathode ray on said screen, means including a pair of deflecting plates for deflecting said cathode ray, said anode being mounted immediately adjacent to said deflecting means at their side facing said cathode and being connected to a source of constant anode potential, and a deflecting voltage transformer the secondary winding of which is connected to said deflecting plates; a circuit additionally connecting each of said plates via a rectifier to said anode so that the instantaneous negative of said plates is raised to anode potential.

4. In a cathode ray tube arrangement comprising means including a cathode for producing a cathode ray, a screen, means including an anode for focusing said cathode ray on said screen, means including a pair of deflecting plates for deflecting said cathode ray, said anode being mounted immediately adjacent to said deflecting means at their side facing said cathode and being connected to a source of constant anode potential, and a deflecting voltage transformer; a circuit comprising two leakage resistances each connecting one of said plates to said anode, and two thermionic tubes each being provided with cathode, control grid, anode, a high grid resistance and an anode resistance, the cathodes of said thermionic tubes being connected to the mean point of the secondary of said deflection transformer, said grids via said grid resistance to the terminals of said secondary, and the anodes of said thermionic tubes each to one of said plates.

5. In a cathode ray tube arrangement comprising means including a cathode for producing a cathode ray, a screen, means including an anode for focusing said cathode ray on said screen, means including a pair of deflecting plates for deflecting said cathode ray, said anode being mounted immediately adjacent to said deflecting means at their side facing said cathode and being connected to a source of constant anode potential, and means for connecting said deflecting plates with a relaxation generator adapted to produce reverse phase deflecting potentials symmetrical to the potential of said anode; means for producing the effect of a common bias applied to said deflecting plates, which is positive with respect to said anode and varies in rhythm with the deflecting voltage built up across said deflecting plates, the peak value of said bias being substantially equal to one half of the peak value of said deflecting voltage.

6. In a cathode ray tube arrangement comprising means including a cathode for producing a cathode ray, a screen, means including an anode for focusing said cathode ray on said screen, means including a pair of deflecting plates for deflecting said cathode ray, said anode being mounted immediately adjacent to said deflecting means at their side facing said cathode and being connected to a source of constant anode potential, and means for connecting said deflecting plates with a relaxation generator adapted to produce reverse phase deflecting potentials sym-

metrical to the potential of said anode: means for producing the effect of a common bias of linear wave form applied to said deflecting plates, which is positive with respect to said anode and varies in rhythm with the deflecting voltage built up across said deflecting plates, the peak value of said bias being substantially equal to one-half of the peak value of said deflecting voltage.

7. In a cathode ray tube arrangement comprising means including a cathode for producing a cathode ray, a screen, means including an anode for focusing said cathode ray on said screen, means including a pair of deflecting plates for deflecting said cathode ray, said anode being mounted immediately adjacent to said deflecting means at their side facing said cathode

5 and being connected to a source of constant anode potential, and means for connecting said deflecting plates with a relaxation generator adapted to produce reverse phase deflecting potentials symmetrical to the potential of said anode: means for producing the effect of a common bias of linear wave form applied to said deflecting plates, which is positive with respect to said anode and varies in rhythm with the deflecting voltage built up across said deflecting plates, the peak value of said bias being substantially equal to one-half of the peak value of said deflecting voltage, said last mentioned means consisting of a circuit adapted to suppress the 10 15 actually negative wave of said deflecting voltage.

KURT SCHLESINGER.
